CLAIM

The ornamental design for a micrometer, as shown and described.

DESCRIPTION

FIG. 1 is a front elevational view of the micrometer;
FIG. 2 is a rear elevational view thereof;
FIG. 3 is a right-side elevational view thereof;
FIG. 4 is a left-side elevational view thereof;
FIG. 5 is a top plan view thereof;
FIG. 6 is a bottom plan view thereof;
FIG. 7 is a front, left-side, top perspective view thereof; and,
FIG. 8 is a front, right-side, bottom perspective view thereof.
The broken lines depict portions of the micrometer that form no part of the claimed design.
